UNITED STATES PATENT OFFICE.

THOMAS M. JONES, OF GARDEN CITY, KANSAS.

CONCRETE FORM.

Application filed February 21, 1927. Serial No. 169,943.

This invention relates to a form designed primarily for use in producing checks for irrigating ditches of that type shown, for example, in my co-pending application of even date herewith.

It is an object of the invention to provide a collapsible form which can be set up readily for use in an irrigating ditch, the construction of the form being such that, after it has been properly set up, concrete can be poured thereinto so as to produce a one-piece check extending along the bottom and up the sides of the ditch where it will constitute an efficient abutment for a gate and a protection for the bottom and walls of the ditch where the water flows over the gate.

A further object is to provide a form of this character which is cheap to manufacture, light and durable, and can be readily set up for use and easily taken apart.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred forms of the invention have been shown.

In said drawings:

Figure 1 is a front elevation of the form.
Figure 2 is a top plan view thereof.

Figure 3 is a section on line 3—3, Figure 2, the form being shown set up for use in a ditch.

Figure 4 is a section on line 4—4, Figure 1, the form being shown positioned in a ditch.

Figure 5 is a section through the form on line 5—5, Figure 4.

Figure 6 is a section through a portion of one side of the form taken on the line 6—6, Figure 3.

Figure 7 is a front elevation of a portion of a form provided with a supplemental plate for retaining concrete.

Figure 8 is a plan view of a portion of the modified structure illustrated in Figure 7.

Referring to the figures by characters of reference 1 designates side panels formed

of wood or any other suitable material having their front and back edges converging upwardly as shown at 2. Along the outer side of each of these side panels are secured cleats 3 arranged at the edges of the panels parallel therewith, the cleats therefor converging upwardly as will be obvious and as shown in Figure 2. To the bottom portion of each cleat is bolted or otherwise attached a metal strap 4 or the like which lap and is attached to a bottom strip 5 bridging the space between the side panels 1. These bottom strips 5 are arranged in the same planes as the cleats 3 to which they are attached and are held against the lower edges of the side panels as shown. Brackets 6 or the like are attached to the panels 1 and are connected by a brace strip 7 extending from one side to the other of the form. An open space is provided between the lower edges of the panels 1.

In using the form a shallow depression is dug transversely within the bottom of an irrigating ditch D, this depression being shown at d. Additional depressions are formed in the sides of the ditch at the ends of the depressions d as shown at e. The form is then placed in position with the bottom strips 5 resting in the depressions d and with the cleats 3 resting in the depressions e. With the form thus located concrete is poured into the spaces between the side panels 1 and the cleats 3 and the dirt walls of the depressions e. Thereafter an additional quantity of concrete is poured into the depressions d and is leveled off flush with the top edges of the strip 5. This top surface of the bottom thus produced is preferably slightly below the level of the bottom of the ditch as will be apparent by referring to Figure 4. After the concrete has set the form is removed, leaving a one-piece concrete check extending along the bottom and up the sides of the ditch, the sides of the check converging upwardly, said sides in turn diverging upwardly relative to each other, and both sides being integral with the bottom of the check.

Should the form be located at a point where the wall of the ditch cannot be used conveniently for holding the concrete as it is poured between the cleats 3, a retaining member of wood, sheet metal or the like and which has been illustrated at 8 can be attached to the outer edges of the cleats 3 by means of clamps 9, bolts, or any other suit-

able devices. Thus the concrete will be properly retained when poured between the cleats.

When the form is not in use the straps 4 5 can be unfastened from the bottom strips 5, the brace 7 can be detached from the brackets 6, and the entire form collapsed into a small bundle which can be conveniently carried.

10 The form constituting this invention can have its side panels formed of sheet metal, wood or any other desired material. If formed of sheet metal the cleats along the converging edges could of course be made 15 integral with the panels.

What is claimed is:

1. A form of the class described including side panels diverging upwardly and each having upwardly converging front and 20 back edges, a brace interposed between and connecting the side panels, cleats upon the outer sides of said panels along the converging edges thereof, and bottom strips connecting the cleats of opposed panels, there 25 being an open space between the bottoms of the side panels.

2. A form for molding concrete checks, including upwardly diverging side panels having upwardly converging edges, cleats 30 upon the outer faces of the panels and along

said upwardly converging edges, a brace interposed between and detachably connected to the panels, each panel and its cleat cooperating with the side wall of a ditch to form a concrete receiving space, and bottom 35 strips connecting the corresponding cleats of opposed side panels, there being an open space between the lower edges of the side panels, said bottom strips cooperating to retain concrete poured into the space between 40 the strips and beneath the lower edges of the side panels.

3. A form for use in the production of one-piece concrete checks for irrigating ditches, including upwardly diverging side 45 panels each having upwardly converging edges, cleats upon the outer faces of the panels along the converging edges, a brace interposed between and connected to the panels, bottom strips connected to the cleats 50 and extending across the space between the side panels, and means cooperating with the cleats and the side panels for forming concrete receiving spaces, there being an open space between the bottom strips and the 55 lower edges of the side panels to receive concrete to form the bottom of a check.

In testimony that I claim the foregoing as my own, I have hereto affixed my signature.

THOMAS M. JONES.
